MAGICIAN'S DEVICE

Harry Dobrin, New York, N. Y.

Application January 13, 1945, Serial No. 572,646

8 Claims. (Cl. 272—8)

The present invention relates to magicians' devices and more particularly to devices such as, for example, a slate of special construction adapted for use by magicians or mentalists in executing tricks or feats of mind reading.

The primary object of the present invention is to provide improved locking or holding means for the foldable concealing part of a panel of a magician's or mind reader's slate or similar article. In one form of the invention, the panel of the device has a writing-surface part normally concealed by the movable part of the panel, while in another form of the invention the panel is provided with a mirror which is normally concealed by the foldable part of the panel.

The above and other objects, features and advantages of the present invention will be fully understood from the following description considered in connection with the accompanying illustrative drawing.

In the drawing:

Fig. 1 is a plan view of a magician's slate embodying the present invention, portions of the frame being cut away for the purpose of illustration;

Fig. 2 is a sectional view on the line 2—2 of Fig. 1 and shows in dotted lines an intermediate position of the foldable or concealing part of the panel;

Fig. 3 is a sectional view on the line 3—3 of Fig. 1;

Fig. 4 is a sectional view on the line 4—4 of Fig. 1;

Fig. 5 is a fragmentary plan view of a magician's slate provided with a concealable part.

Referring now to the drawing in detail, the device 10 embodying the present invention consists as here shown of a framed slate of a size which can be conveniently manipulated by the magician or mind reader and conveniently held in one of his hands while he writes with his other hand on either side of the slate in the view of the audience. The frame of the slate comprises the opposite side members 12 and the opposite end members 14 and 16, respectively. Said frame is provided with an internal peripherally continuous groove 18 within which the panel indicated as a whole by the numeral 20 is slidably mounted, the marginal side and edge portions of the panel being overlapped at both surfaces thereof by the frame members. It will be understood that panel 20 is slidable longitudinally of side members 12 of the frame in directions toward and away from end members 14 and 16 of the frame.

Panel 20 comprises a backing member 22 of

the same area as the panel, said backing member being formed of suitably stiff cardboard as in the usual slate of the type to which this invention relates. One side surface of backing member 22 of the panel is completely covered by a sheet or layer 24 of slate-simulated material, whereby said side of the panel is provided with a black writing surface. Said sheet 24 consists of thin cardboard coated on its outer surface with silicate paint, said coating providing the writing surface, the inner surface of sheet 24 being adhesively secured to the adjacent surface of backing member 22. The other side of backing member 22 is also provided with a black writing surface constituted by a silicate paint coated sheet having the foldably related parts 26 and 28 and by a silicate paint coated sheet having the foldably related parts 30 and 32. Said sheets are preferably formed of the same material as sheet 24. The fold lines between parts 26 and 28 of one of the sheets is indicated at 34 and the fold line of parts 30 and 32 is indicated at 36, said fold lines extending transversely of the panel for the full width of said sheets. Part 25 26 of the one of the sheets is adhesively secured to the adjacent surface of backing member 22 except at the portion thereof which overlies a transversely extending recess 38 which is provided in backing member 22 by removing a portion 15 of the material thereof. Recess 38 extends for the full width of the backing member as indicated by the laterally spaced dotted lines 38A in Fig. 1. Sheet parts 28, 30 and 32 are free from direct securement to backing member 22, and 20 sheet parts 28 and 32 are adhesively united to each other in surface to surface relation and form the foldable member or panel part 40. Reinforcing strips 42 and 44 of thin sheet metal are secured adhesively, preferably by rubber cement to the inner surface portions of sheet parts 26 and 30 adjacent the fold lines 34 and 36. Said 25 reinforcing strips 42 and 44 are preferably of a thickness approximately equal to the depth of recess 38 and are positioned in said recess, said 30 reinforcing strips extending for the full width of the sheet parts 26 and 30 transversely of the panel. Recess 38 eliminates the formation of a bulge in the panel at the fold lines 34, 36, and strips 42 and 44, besides reinforcing sheet parts 45 26 and 30, aid in defining the fold line of movable panel part 40 and also provide a firm backing for the portions of the writing surface of the panel which are positioned over recess 38.

Foldable member 40 of the panel is narrower than the panel proper whereby said foldable

member is movable from a down folded position at one side of the fold or hinge line of said member to a down folded position at the other side of said fold line. More particularly, the width of folding member 40 is approximately equal to the distance between the confronting inner edges 12A of side panel members 12. When foldable member 40 is in one of its down folded positions, for example, that illustrated in Fig. 1, in which it overlies sheet part 30, the corresponding part of the panel is concealed by said foldable member and sheet parts 26 and 28 appear as a continuous surface of the slate, fold line 34 being substantially invisible except upon close inspection. On the other hand, when foldable member 40 is positioned in its other down folded position, that is at the left of its fold line, viewing Figs. 1 and 2, the corresponding part of the panel is concealed by said foldable member, and sheet parts 30 and 32 appear as one continuous writing surface of the slate, fold line 36 being substantially invisible except upon close inspection. Said panel part 40 is stiff enough to be self sustaining by virtue of the double thickness thereof and the interposed adhesive which unites the two thicknesses. However, when the slate is large and the foldable panel part is correspondingly large, said part can be stiffened by strips of thin sheet metal disposed between the parts 28 and 32 at the side and top marginal edge portions thereof and secured in position by rubber cement or any other suitable adhesive.

In either of the down folded positions of foldable member 40, it is held or locked releasably in down folded position by the overlapping edge portion of frame member 14 or frame member 16. Thus, as illustrated in Fig. 1 foldable member 40 is received in the groove of end frame member 16 and is thus releasably locked or held in down folded position in abutting surface relation to sheet part 30. On the other hand, when foldable member 40 is down folded against sheet part 26, the marginal end portion of said foldable member is positioned in the groove of the other end frame member 14 and is thus releasably locked or held in said down folded position. When it is desired to release foldable member 40 from one of its down folded positions in which it is retained by the companion or adjacent frame member, panel 20 as a whole is shifted or slid in the grooves of side frame members 12 toward the opposite end frame member sufficiently to release the foldable member to permit the pivotal movement thereof to its other down folded position, after which panel 20 is slid in the opposite direction to permit the free end of foldable member 40 to slide into the groove in the adjacent end frame member, and finally the panel 20 is moved towards said last mentioned frame member so as to engage the free end of the foldable member in the groove of the frame member. Thus, it will be noted that the device of the present invention has a double locking or retaining construction for the foldable member or panel part 40 of the slate, while at the same time, the panel 20 can be easily manipulated to facilitate the movement of panel 40 by the magician or mentalist to either of its down folded and locked positions, and it will be understood that this shifting of the foldable panel member 40 can be readily accomplished by the magician or other person having the usual dexterity and skill without detection by the audience during the performance. When panel part 40 is pivotally moved from one down folded position to the

other down folded position thereof, part 30 moves longitudinally of the frame in the grooves of frame members 12, this movement being possible because said part 30 is not secured to the underlying surface of panel member 22. In the case of large slates, it is advisable to reinforce part 30 by a sheet of thin metal secured by rubber cement or in any other suitable way to the under surface of part 30.

10 Notches 46 are provided in sheet parts 26 and 30 at the opposite ends of the fold line of panel member 40 to improve the foldability of panel part 40. Further as here shown, strips 48 of thin cardboard are provided at one side of the panel, said strips terminating short of the adjacent end frame members 14 and 16 so that a small amount of clearance is provided in the corresponding portions of the grooves of side members 12 to enable the manipulator of the slate to press the end portion of the panel transversely of the plane thereof in said portions of the grooves to facilitate the entrance of the free end portion of the foldable member 40 in the groove of the adjacent end frame member during the operation of locking said foldable member in the groove of said end frame member. Reinforcing strips 49 are secured to the marginal side portions of sheet part 26 to compensate for the additional thickness of one sheet part of the foldable member 40.

30 It will be understood by users of devices of the type to which this invention relates that the slate 10 can be used in performing various tricks of the kind performed by magicians or mentalists in presenting mind reading performances or in performing other feats or tricks. In general, it will be understood that preliminary to the giving of the performances, various numbers or other writings are applied by chalk to the outer surfaces of either the portions 30 and 32 or the portions 26 and 28, the outer surfaces of portions 26 and 28 being blank when either portion 30 or 32 or both of said last mentioned portions have writing thereon and portions 30 and 32 being blank when either portions 26 or 28 or both of said last mentioned portions have writing thereon so that when foldable member 40 is in one of its down folded positions, the writing is concealed by said foldable member, later to be uncovered at some point of the performance of the trick or feat, by moving the foldable member to its other down folded position.

55 In the form of the invention illustrated in Fig. 5, the device 10A is of the same construction as the device 10 except that a plane mirror 50 is adhesively secured to a part of panel member 22A in position to be concealed by the foldable member 40A which is of the same construction as the foldable member 40 of the device 10. In other words, in device 10A sheet portion 30 is omitted and foldable member 40A consists of adhesively united sheet portions 28A and 32A which correspond to sheet portions 28 and 32, respectively, of device 10, sheet portion 28A being integral with sheet portion 26A which corresponds to sheet portion 26 of device 10. The fold line of foldable member 40A is indicated at 34A and corresponds to the fold line 34 of device 10. The frame of device 10A is the same as the frame of the device 10 and except for the differences hereinbefore described, panel 20A of device 10A is the same as panel 20 of device 10, panel 20A being slidably in the frame in the manipulation of the device for releasably locking foldable member 40A in either of its down folded positions in the same way described above with reference to the ma-

nipulation of the device for releasably locking foldable member 40 of device 10 in either of the down folded positions of foldable member 40. In Fig. 5 the foldable member 40A is in the position in which the mirror is exposed for use by the magician or mentalist in performing the trick or feat of mind reading, but normally when the device is in a position in which it can be seen by the audience, foldable member 40A is in its other down folded position in which it completely conceals the mirror. Thus, as will be readily understood, device 10A constitutes a writing slate provided with a concealed mirror. It will be understood that the outer surface of mirror 50 is substantially flush or raised but slightly above the adjacent surface of panel member 22A.

It will be understood that various changes in the details of construction and in the arrangement of parts may be made in the devices of the present invention without departing from the underlying idea thereof within the scope of the appended claims.

Having thus described my invention, what I claim and desire to secure by Letters Patent is:

1. A device of the character described, comprising a frame, a writing panel slidably mounted in said frame, and a flat member foldably connected to said panel along a line close to one surface of said panel and extending transversely of said surface medially thereof, said foldable member being movable from one down folded position in which it overlies and conceals a portion of said surface at one side of said medial line to a down folded position in which it overlies a portion of said surface at the other side of said medial line, and exposes said first mentioned surface portion, both surfaces of said foldable member having the same surface appearance as at least one of said panel surface portions, said foldable member being releasably engageable with said frame by sliding said panel in said frame for releasably retaining said foldable member in either of said down folded positions thereof.

2. An article of the character described comprising a frame having internally grooved side and end members, a writing panel mounted in said frame and having its marginal edge portions slidable in said grooves, and a flat member foldably connected to said panel along a line close to one surface of said panel and extending transversely thereof between said side members of the frame, said foldable member being movable from one down folded position in which it overlies and conceals a portion of said surface at one side of said line to a down folded position in which it overlies a portion of said surface at the other side of said line, and exposes said first mentioned surface portion, both surfaces of said foldable member having the same surface appearance as at least one of said panel surface portions, the outer end portion of said foldable member being receivable in the groove of either of said end members by sliding the panel in the grooved side members of the frame whereby said foldable member is releasably held in either of said down folded positions by said end frame members, respectively.

3. An article of the character described comprising a writing panel having a backing member, a layer of sheet material having a part secured to and covering a surface portion of said backing member, said layer of sheet material having an integral foldable part free from securing to said backing member, said foldable part being foldably connected to said secured part along a

line extending transversely of said backing member close to said surface portion thereof and having one surface continuous with the outer surface of said secured part, and a layer of sheet material having a part secured to the other surface of said foldable part, said last mentioned layer having an integral part positioned in overlying covering relation to said backing member in movable relation thereto, the first mentioned part of said last mentioned layer being foldable as a unit with said other foldable part at said transverse line and constituting a foldable member movable at said transverse fold line from one down folded position at one side of said line in which it overlies and conceals the outer surface portion of the secured part of the first mentioned layer to a down folded position at the other side of said transverse line for concealing said backing-covering part of said last mentioned layer, the exposed surfaces of said layers having the same surface appearance, and means for releasably holding said foldable member in either of said down folded positions thereof.

4. An article of the character described comprising a writing panel having a backing member, a layer of sheet material having a part secured to and covering a surface portion of said backing member, said layer of sheet material having an integral foldable part free from securing to said backing member, said foldable part being foldably connected to said secured part along a line extending transversely of said backing member close to said surface portion thereof and having one surface continuous with the outer surface of said secured part, and a layer of sheet material having a part secured to the other surface of said foldable part, said last mentioned layer having an integral part positioned in overlying covering relation to said backing member in movable relation thereto, the first mentioned part of said last mentioned layer being foldable as a unit with said other foldable part at said transverse line and constituting a foldable member movable at said transverse fold line from one down folded position at one side of said line in which it overlies and conceals the outer surface portion of the secured part of the first mentioned layer to a down folded position at the other side of said transverse line for concealing said backing-covering part of said last mentioned layer, the exposed surfaces of said layers having the same surface appearance, and a frame having side members in which said panel is mounted and end members releasably engageable with said foldable member in said down folded positions, respectively, thereof for releasably holding said foldable member in either of said down folded positions thereof.

5. An article of the character described comprising a writing panel having a backing member, a layer of sheet material having a part secured to and covering a surface portion of said backing member, said layer of sheet material having an integral foldable part free from securing to said backing member, said foldable part being foldably connected to said secured part along a line extending transversely of said backing member close to said surface portion thereof and having one surface continuous with the outer surface of said secured part, and a layer of sheet material having a part secured to the other surface of said foldable part, said last mentioned layer having an integral part positioned in overlying covering relation to said backing member in movable relation thereto, the first mentioned part of said last mentioned layer being foldable as a unit with said

other foldable part at said transverse line and constituting a foldable member movable at said transverse fold line from one down folded position at one side of said line in which it overlies and conceals the outer surface portion of the secured part of the first mentioned layer to a down folded position at the other side of said transverse line for concealing said backing-covering part of said last mentioned layer, the exposed surfaces of said layers having the same surface appearance, means stiffening and reinforcing said layers of sheet material adjacent said fold line, and means for releasably holding said foldable member in either of said down folded positions thereof.

6. A device of the character described comprising a panel having a backing member, a mirror carried by said backing member at one side thereof and covering a surface part thereof, a layer of sheet material at said side of the backing member and secured to an adjacent surface part of said backing member, and a foldable member foldably connected to said layer of sheet material along a line close to the surface of the backing member at said side thereof, said foldable member being movable at said fold line from a down folded position in which it covers and conceals said mirror and appears as a continuation of said layer to a down folded position in which it overlies said layer and exposes said mirror, and means for releasably holding said foldable member in either of said down folded positions thereof.

7. A device of the character described comprising a panel having a backing member, a mirror carried by said backing member at one side there-

of and covering a surface part thereof, a layer of sheet material at said side of the backing member and secured to an adjacent surface part of said backing member, and a foldable member foldably connected to said layer of sheet material along a line close to the surface of the backing member at said side thereof, said foldable member being movable at said fold line from a down folded position in which it covers and conceals said mirror and appears as a continuation of said layer to a down folded position in which it overlies said layer and exposes said mirror, and a frame having side members in which said panel is mounted and end members releasably engageable with said foldable member in said down folded positions, respectively, thereof for releasably holding said foldable member in either of said down folded positions thereof.

8. A device of the character described, comprising a frame, a writing panel slidably mounted in said frame, and a flat member foldably connected to said panel along a line close to one surface of said panel and extending transversely of said surface medially thereof, said foldable member being movable from one down folded position in which it overlies and conceals a portion of said surface at one side of said medial line to a down folded position in which it overlies a portion of said surface at the other side of said medial line, and exposes said first mentioned surface portion, said two panel surface portions and both side surfaces of said foldable panel member having the same surface appearance.

HARRY DOBRIN.
